[57] ABSTRACT

Removal of suspended particulate material in the secondary liquid circulated through a vapor generator of the shell and tube type is effected by the arrangement in the shell interior of baffle means defining a settling chamber therein. The baffle means is operative to retard the flow of secondary liquid and to effect an abrupt change in its direction of flow through the settling chamber whereby the suspended particles are caused to gravitate to the bottom thereof. Continuous or periodic flushing of the settling chamber is effected through a perforated blowdown pipe.

FIG. 3

STEAM GENERATOR BLOWDOWN APPARATUS

BACKGROUND OF THE DISCLOSURE

The present invention relates in general to vapor generators of the shell and tube type wherein vaporizable liquid, termed the secondary liquid, is transformed into vapor by passing it in heat exchange relation with the high temperature primary fluid that is conducted through the tubes. Vapor generators of this type characteristically employ a bundle of tubes, either of the inverted U-type in which both ends of each tube are connected to a single tube sheet or of the straight type in which the tubes are connected at their opposite ends to a pair of axially spaced tube sheets. The units operate with a body of secondary liquid maintained at a predetermined level in a downcomer annulus and a riser passage with circulation of the liquid between the two sections being maintained by the thermal syphonic action created by the difference in densities between the liquid bodies in the respective sections.

Conventionally, the secondary liquid flow through vapor generators of the described type is such that the liquid from the down-comer annulus enters the riser passage from its periphery and must turn and flow upwardly therethrough. This flow pattern creates a region of relatively stagnant flow in the lower part of the riser passage within which any suspended particles entrained in the secondary liquid, such as metal oxides or scale-forming calcium, may be permitted to settle thereby forming sediment deposits. Such deposits, if not removed, may cover the tube and tube sheet surfaces thereby operating to reduce the amount of heat transfer area provided thereby. Additionally, sediment deposits provide a convenient medium for the concentration of corrosive impurities, such as chloride salts, or the like, which can attack the tube material and may result in tube failure thereby requiring shutdown of the plant.

Although the removal of sediment deposits has traditionally been provided by blowdown procedures in which the affected area receives a periodic or continuous flushing with relatively high velocity fluid, such procedures have become increasingly difficult as the capacity of shell and tube type vapor generators has increased. Increased unit capacities require a greater number of tubes disposed within the shell and, because of the desire to maintain the vapor generator shell as small as possible, there has been a tendency to accommodate the increased number of tubes by placing the tubes on closer spacing. Thus, blowdown is impeded since space is no longer available to accommodate the piping required to adequately flush all potentially affected regions of the tube bundle. To remove rows of tubes in order to accommodate additional blowdown piping is uneconomic because of the resultant loss of heat transfer area.

It is to the solution of such problems that the present invention is directed.

SUMMARY OF THE INVENTION

According to the present invention there is provided in a vapor generator of the shell and tube type baffle means defining an annular settling chamber forming a low liquid flow velocity region within the interior of the shell. The settling chamber has an opening for the reception of secondary liquid flowing within the unit and defines a flow path in which the secondary liquid under-

5 goes an abrupt change of direction whereby the entrained particulate material will gravitate therefrom. A blowdown pipe is operatively disposed in the settling chamber in communication with the exterior of the shell whereby sediment blowdown can be effected on a continuous or periodic basis.

10 In vapor generators whose pressure shells comprise an enlarged diameter upper shell portion, a reduced diameter lower shell portion and a conical transition member interconnecting the two, in accordance with an aspect of the invention the baffle plate is conveniently disposed to cooperate with the transition member in defining the settling chamber. It should be understood, however, that the invention is equally applicable 15 to shell and tube vapor generators having other shell configurations.

For a better understanding of the invention, its operating advantages and the specific objects obtained by its use, reference should be made to the accompanying 20 drawings and description which relate to a preferred embodiment of the invention.

BRIEF DESCRIPTION OF THE DRAWINGS

FIG. 1 is a vertical section of a typical shell and tube 25 vapor generator equipped with apparatus of the present invention;

FIG. 2 is an enlarged partial vertical section of the vapor generator of FIG. 1 illustrating the settling chamber of the present invention in greater detail;

30 FIG. 3 is a plan section taken along line 3—3 of FIG. 2; and

FIG. 4 is an enlarged partial vertical section of an alternative form of the settling chamber of the invention.

35 DESCRIPTION OF THE PREFERRED EMBODIMENT

In FIG. 1 of the drawings, there is shown a shell and tube type vapor generator 10 incorporating the present invention. It comprises a vertically elongated pressure 40 vessel defined by a lower cylindrical shell section 12 and a larger diameter, upper cylindrical shell section 14, the latter being integrally connected with the former by means of a frustoconical transition member 16. The ends of the vessel are closed, at the bottom by 45 means of hemispherically formed closure head 18 and at the top by a dome-shaped cover 20 containing a vapor outlet nozzle 22. The interior of the pressure vessel contains a plurality of annular baffles 24, 26 and 28, baffle 24 being a cylindrical shroud extending in coaxially spaced relation from the wall of the lower shell 12 to cooperate therewith in forming an inner riser passage 30 and an outer, annular downcomer passage 32. The lower end of the vessel interior is closed by tube sheet 34 disposed between the lower end of shell 12 and the lower closure head 18. The tube sheet 34 extends transversely of the vessel axis and connects at its periphery between the shell 12 and closure head 18. The tube sheet 34 contains a plurality of tube openings 50 adapted to fixedly receive the ends of inverted U-shaped heat transfer tubes 38 that form a longitudinally extending tube bundle 40 substantially filling the riser passage 30. The tube ends are open and extend through the tube sheet to place the tubes 38 in fluid communication with a heating fluid chamber that occupies that 55 region of the vessel enclosed between the closure head 18 and the tube sheet 34 and which is divided into inlet and outlet portions 44 and 46, respectively, by means

of a diametral plate 48. The heating fluid chamber is, in turn, connected to a source of heating fluid (not shown) by means of inlet and outlet nozzles 50 and 52, respectively, that communicate with the respective chamber portions 44 and 46 and thereby effect circulation of heating fluid through the tubes 38.

Feedwater is supplied to the unit through an inlet nozzle 54 that is shown penetrating the upper shell 14. A ring header 56 connects with the nozzle 54 and serves to distribute feedwater passed through the nozzle about the circumference of the downcomer passage 32 discharging into the passage by means of downwardly-directed discharge ports 58. Flow of feedwater from the downcomer passage 32 into the riser passage 30 is effected by the vertically spaced relationship that exists between the lower end of the cylindrical baffle plate 24 and the upper surface of tube sheet 34. Within the riser passage the feedwater is caused to flow in heat exchange relation with the tubes 38 where heat is extracted from the heating fluid circulated therethrough to cause some of the feedwater to be transformed into vapor. The so-created vapor-liquid mixture flows to the upper region of the vapor generation chamber formed as a mixture collection chamber indicated as 60. From the mixture collection chamber 60 the flowing mixture is passed to vapor-liquid separator apparatus, a multiplicity of such separators indicated as 62 being mounted upon baffle plate 28 and communicating with the chamber 60 by means of openings 61 provided in the baffle. The separators 62 may be of any well known construction, those shown being of the centrifugal type, and are arranged to discharge separated liquid downwardly upon the baffle plate 28 from whence it is returned to the downcomer passage 32 to be mixed with the incoming feedwater and recirculated through the unit. The separated vapor, on the other hand, is discharged from the separators 62 in the upward direction for discharge out of the vapor outlet nozzle 22 from whence it is conducted to a point of use.

According to the present invention an annular baffle 64 is provided in the upper region of the downcomer passage 32. The baffle 64 is concentrically spaced between the cylindrical shroud 24 and the interior surface of the pressure shell. As shown, the baffle 64 is preferably disposed adjacent the transition member 16 to cooperate therewith in defining a settling chamber 66. The lower end of the baffle plate 64 is sealedly attached, as by means of welding, to the juncture of the transition member 16 and the lower shell section 12, thereby forming the closed bottom of the chamber 66. At its upper end the baffle plate 64 possesses an outwardly flange 68 intended to prevent flow of secondary liquid directly into the lower region of the downcomer passage 32. The end edge of the flange is disposed in close concentric spacing with respect to the adjacent surface of the shroud 24 in order to accommodate thermally induced relative movements between the shroud and the shell.

Adjacent the flange 68 the baffle plate defines an inlet opening, indicated as 70, to the settling chamber 66. As shown, this opening is disposed below the discharge ports 58 of the feedwater inlet header 56 whereby the secondary liquid admitted to the settling chamber 66 is a mixture of the fresh, incoming feedwater and separated liquid from the separators 62, the latter being recirculated through the unit.

The baffle plate 64 is imperforate over a principle portion of its length to render the settling chamber 66 a region of relatively low liquid velocity. Adjacent its upper end, however, the plate is provided with a plurality of openings 72 which establish fluid communication between the settling chamber and the remainder of the downcomer passage 32. By means of this arrangement the secondary liquid entering the settling chamber, in addition to having its flow velocity reduced, is also caused to undergo an abrupt reversal of direction as shown by the arrows 74 whereby entrained particulate material is removed from the flow stream by gravity and falls as sediment to the bottom of the chamber.

An annular blowdown pipe 76 is disposed in the lower region of the settling chamber 66. The pipe is perforated, as at 78, along its length and communicates with the exterior of the pressure shell through blowdown nozzle 80 which is, as shown in FIG. 3, T-connected to the pipe. Means (not shown) connect with the blowdown nozzle 80 whereby blowdown of the removed particulate material can be effected on either a continuous or a periodic basis.

In FIG. 4 of the drawing there is illustrated an alternative form of the invention in which the perforated baffle plate 64 of the FIG. 1 embodiment is replaced in the settling chamber 66 by a baffle arrangement comprising members 82 and 84 which define a tortuous fluid path between the settling chamber and the remainder of the downcomer passage 32. Member 82 is an imperforate annular plate disposed in concentrically spaced relation between the cylindrical shroud 24 and the transition member 16. Its lower end edge is weldedly attached at the juncture of the transition member 16 and the lower shell section thereby defining the bottom of the settling chamber 66. The member 84 is an annular plate, angular in section which is weldedly attached about its inner peripheral edge to the shroud 24. As shown the member 84 is vertically spaced above the upper end edge of the member 82 and telescopically encloses the same to define a fluid path by means of which the flowing secondary liquid is caused to undergo an abrupt change of direction prior to exiting the settling chamber 66 whereby to induce gravitational removal of entrained particulate material for discharge through blowdown pipe 76 in a manner similar to that effected by the arrangement shown in FIG. 1.

It will be appreciated that apparatus as herein-described provides a convenient solution to the problem of removing sediment forming particulate material from the secondary liquid that is circulated through shell and tube vapor generators. Because the arrangement requires no blowdown piping within the interior of the tube bundle, spaces that could only be produced by the removal of heat exchange tubes are not required. Moreover, because the settling chamber and its attendant blowdown piping is located in the downcomer passage remote from the tube bundle no heat transfer surface is obstructed by the blowdown apparatus. This, of course, enables more effective use of the heating surface provided by the tube bundle.

While the preferred embodiment of the present invention has been described herein, it should be understood that the description is merely illustrative and that variations and modifications can be made without departing from the spirit and scope of the invention. For example, the invention is not limited in its application to shell and tube vapor generators employing inverted

U-tubes as in the described embodiment. The invention can be equally applied within the downcomer passage of vapor generators of the straight tube type.

What is sought to be protected herein is as recited in the appended claims.

What is claimed is:

1. In a shell and tube heat exchanger for the generation of vapor by the indirect transfer of heat from a heating fluid to a secondary liquid including a pressure shell having a transverse tube sheet defining a vapor generating region enclosing a bundle of heat exchange tubes emanating from said tube sheet, means for passing heating fluid through said tubes and means for circulating said secondary liquid through said vapor generating region exteriorly of said tubes, the improvement comprising means for the removal of suspended particulate material from said circulating secondary liquid, said means including:

- a. a baffle means defining a settling chamber forming a low liquid flow velocity region within the interior of said pressure shell;
- b. said settling chamber having an opening for the reception of secondary liquid flowing within said vapor generating region and defining a flow path in which said secondary liquid undergoes an abrupt change of direction; and
- c. a blowdown pipe operatively disposed in said settling chamber and communicating with the exterior of said pressure shell for the discharge of settled particulate material from said settling chamber.

2. The organization according to claim 1 in which said heat exchanger includes a generally cylindrical baffle enclosing said bundle of heat exchange tubes in circumferentially spaced relation from the interior surface of said pressure shell to define an axial riser passage and an annular downcomer passage and said settling chamber is disposed in said downcomer passage.

3. The organization according to claim 2 in which

said secondary liquid circulating means includes feed-water inlet means communicating with said downcomer passage upstream in the secondary liquid flow sense from said settling chamber.

5 4. The organization according to claim 2 in which said baffle means includes a substantially cylindrical plate concentrically spaced between said cylindrical baffle and the interior surface of said pressure shell defining an annular settling chamber about said downcomer passage, said plate being imperforate at least over a substantial portion of its length.

10 5. The organization of claim 4 in which said baffle plate includes an out-turned flange disposed adjacent the inlet opening of said settling chamber, said flange having an end surface in closely spaced concentric relation to said cylindrical baffle, and means forming perforations in said baffle plate adjacent said flange.

15 6. The organization of claim 4 in which said pressure shell includes an enlarged diameter upper shell portion and a reduced diameter lower shell portion, a conical transition member connecting said shell portions, said baffle plate cooperating with the internal surface of said transition member to form said settling chamber.

20 7. The organization of claim 6 in which the lower end 25 of said baffle plate is sealedly connected to said pressure shell at the juncture of said transition member and said lower shell portion.

8. The organization of claim 4 in which said cylindrical plate is attached to said pressure shell and including 30 a second annular member attached to said cylindrical baffle in concentrically spaced relation to said cylindrical plate and cooperating therewith to define a tortuous fluid path between said settling chamber and said downcomer passage.

35 9. The organization of claim 4 in which said second annular member is angular in section and telescopically encloses said cylindrical plate.
